(57) **CLAIM**

The ornamental design for a combined sink and cabinet, as shown and described.

DESCRIPTION

FIG. 1 is a front perspective view of a combined sink and cabinet;

FIG. 2 is a top view thereof;

FIG. 3 is a front view thereof;

FIG. 4 is a right side view thereof; and,

FIG. 5 is a left side view thereof.

The rear of the design is plain and unornamented.

The broken lines shown in the drawings outlining the faucet, drain, handles, and feet of the vanity are for illustrative purposes only and form no part of the claimed design.
